UNITED STATES PATENT OFFICE.

JAMES C. ARMS, OF NORTHAMPTON, MASSACHUSETTS.

IMPROVEMENT IN POCKET-BOOK FASTENINGS.

Specification forming part of Letters Patent No. 82,577, dated September 29, 1868.

To all whom it may concern:

Be it known that I, J. C. ARMS, of Northampton, in the county of Hampshire and State of Massachusetts, have invented certain new and useful Improvements in Pocket-Book Fastenings; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in a novel construction of a clasp for pocket-books and similar articles, as hereinafter more fully explained.

Figure 1 is a front view of a pocket-book with my improved clasp applied thereto. Figs. 2, 3, and 4 are views of the parts in detail; and Figs. 5, 6, 7, and 8 are views of the same device, slightly modified.

To construct my improved clasp, I take a flat piece of sheet metal, C, and cut it out in a die, with points *n* at the corners, which are bent up to form clips, by which it is secured to the pocket book, and with a series of oblong holes, *e*, as represented in Figs. 1 and 3. I then in a similar manner form a slide, D, with T-shaped holes, as shown in Fig. 4, this slide being of proper width to slip under the plate C. I also form a clip, B, with a lip, *a*, standing at right angles to the body, this lip *a* being of proper size to fit into the holes *e* and *o*, and being formed like an inverted T, as shown in Figs. 2 and 3, the neck of this lip being of proper width to enter the narrow part of the hole *o* in the slide D, the clip B being secured to the flap of the pocket-book A by points *n*, or by rivets, as represented in Fig. 1. The parts being thus constructed and attached, as represented in Fig. 1, the slide D is drawn back, and the lip *a* is inserted in one

of the holes *e*, and also through the hole *o*, in the slide D, underneath. The slide D is then shoved forward, the shoulders on each side of the narrow part of the opening locking over the shoulders on the lip *a*, and thus lock the latter securely in place. To release the clip, it is only necessary to draw back the slide D, which has a lip, *b*, at its end for that purpose.

If preferred, the under plate may be formed as represented by E, Fig. 8, and the upper plate F made to slide thereon, the latter being secured to the former by lips *t*, bent around under its edges, as represented in Fig. 5. In this case the lip *a* on the clip B is formed with a hole, *l*, in it, as shown in Fig. 6. When the plates E and F are attached, and their openings made to coincide, the lip *a* is inserted and the plate F is drawn back, which causes the tongue *i* of plate E to enter the hole *l* in the lip *a*, and thus lock it in place. To release the lip, it is only necessary to shove the slide F forward, when it can be withdrawn.

It is obvious that the plates E and F may be attached, either end foremost, the only difference being that the slide will be moved in the opposite direction.

It is also obvious that the plate F may be permanently attached and the plate E made to slide, the result being the same in either case.

By these means I am enabled to produce a simple, cheap, and efficient device, well adapted to the purpose intended.

Having thus described my invention, what I claim is—

The clasp or fastening, consisting of the plate C, slide D, and clip B, or their equivalents, constructed and arranged to operate substantially as and for the purpose herein described.

JAMES C. ARMS.
